UNITED STATES PATENT OFFICE.

HARRY M. SPANGLER, OF DAYTON, OHIO.

SELF-CLEANING WASHSTAND-VALVE.

1,071,271.

Specification of Letters Patent. Patented Aug. 26, 1913.

Application filed September 21, 1911. Serial No. 650,619.

To all whom it may concern:

Be it known that I, HARRY M. SPANGLER, a citizen of the United States, residing at Dayton, in the county of Montgomery, State 5 of Ohio, have invented certain new and useful Improvements in Self-Cleaning Washstand-Valves; and I do hereby declare the following to be a full, clear, and exact description of the invention, such as will 10 enable others skilled in the art to which it appertains to make and use the same.

This invention relates to new and useful improvements in valves and more particularly to the class adapted to be used in connection with washstands or the like.

An object of this invention is the provision of a valve employing the use of a ball which is free to turn in any direction thereby preventing the lodgment of foreign 20 particles between the same and its seat.

Another object of this invention is to improve and simplify devices of this character, rendering them comparatively simple and inexpensive to manufacture, reliable and 25 efficient in use and readily operated.

With the above and other objects in view this invention resides in the novel features of construction, formation, combinations and arrangements of parts to be hereinafter 30 fully described, claimed and illustrated in the accompanying drawing in which:

Figure 1 is a vertical longitudinal sectional view taken through my improved valve, and Fig. 2 is a horizontal sectional 35 view taken on the line 2—2 of Fig. 1.

Referring to the drawing by similar characters of reference throughout the several views, the numeral 5 designates generally a fragment of a washstand in which is located 40 an opening 6 for the reception of my improved valve 7. This valve 7 comprises a cylindrical casing 8 the upper end of which is reduced as indicated by the numeral 9, which reduced portion is partially separated 45 from the valve casing by a horizontal web 10.

The upper end of the reduced portion 9 is exteriorly threaded as at 11 for engagement with locking nuts 12 and 13 which when the said threaded portion is extended through 50 the aperture 6 will engage the opposite faces of the washstand 5 and hold the valve against displacement.

The locking nut 13 is preferably in the form of a cap formed with a central opening 55 15 through which operates a plunger rod 16. A cotter pin 17 extends through an opening

formed in the plunger rod 16 and limits the upward movement thereof by its contact with the lower side of the cap, while the upper terminal of the said rod 16 is threaded 60 to engage a socketed head 18 preferably in the form of a thumb button providing a means whereby this plunger rod can be operated.

The plunger rod 16 contacts with, upon 65 its downward movement, a valve stem 19 slidably located in an opening 20 formed in the horizontal web 10. This stem 19 also passes through a gland 21 formed by enlarging the upper end of the opening 20. A 70 quantity of packing 22 surrounds the stem 19 within the gland 21 and is held therein against displacement by a screw cap 23 threaded within said gland. A head 24 is formed upon the lower end of the stem 19 75 for engagement with a ball valve 25, which is forced upwardly into the socket formed in the lower face of the head 24 and also to engage a seat 26 located at the lower end of the web 10 in the upper extremity of the 80 casing 8.

An outlet 27 projects laterally from the upper end of one side of the casing 8, and communicates with the interior thereof through an L-shaped port 28 which extends 85 centrally through the valve seat 26. An inlet extension 29 projects from the lower end of the casing 8 oppositely to the before mentioned extension 27 and is formed with an opening 30 through which fluid is admitted 90 to the valve casing 8. These said extensions 27 and 29 are each externally threaded for engagement with outlet and inlet conduits which are not shown in the drawing.

The lower end of the valve casing 8 is internally threaded as at 31 to receive a nut or closure 32 while in order to prevent any leakage between the said threads, a gasket 33 is interposed between the lower end of the said casing 8 and a flange 34 formed 100 upon the closure 32. This said closure 32 is further provided with an angular extension 35 which provides a means of engagement with a wrench not shown whereby the said closure may be removed if desired.

A spider 36 is slidably located within the casing 8 and in contact with the inner surface thereof. This spider is formed in its upper face with a socket 37 to engage the ball 25 and in spaced relation from its periphery with a plurality of passages 38 through which fluid passes, in flowing from

the inlet port to the outlet port. The spider 36 has depending from its lower side a concentrically located lug 38 which engages the upper end of a helical spring 39, the lower end of which is engaged by a lug 40 formed upon the upper face of the closure 32 at its central point.

The ball valve 25 is at all times yieldingly held in engagement with the seat 26 through the medium of the spider 36 and spring 39 except when pressure is exerted upon the rod or plunger 16 which causes the downward movement of the valve stem 19 and consequently the downward movement of the valve against the tension of the spring 39 which causes its upward movement as soon as the plunger is released.

It should be noted that the valve 25 is loosely arranged between the seat 26 head 20 and adjacent face of the socket 37 and is permitted to rotate in any direction. This arrangement serves to prevent any foreign matter from clogging in the casing adjacent the ball valve as the passage of water there-through causes the same to rotate after the plunger is released and the valve starts in its movement in the direction of the seat.

From the foregoing disclosures taken in connection with the accompanying drawing it will be manifest that a valve of the nature described is provided for which will fulfil

all of the necessary requirements of such a device.

Having thus fully described this invention what I claim as new and desire to protect by Letters Patent, is:

In a valve of the class described, a casing provided with a reduced upward extension formed with a bore in the lower end thereof, opening into the casing and directed at right angles to the extension at its upper end to form an outlet port, an inlet port formed adjacent the lower end of the casing, a plug threaded into the lower end of the casing, a valve seat formed at the juncture of said bore and the inside of the casing, a plate slidably in the casing, having a plurality of openings formed therein and provided centrally with a concave surface, a ball mounted in the casing between the valve seat and the plate, a coil spring disposed between the plate and the said plug, a rod slidably mounted in the extension, an enlarged head formed on the rod and bearing against the periphery of the ball and means for actuating the said rod to open the valve.

In testimony whereof, I affix my signature, in presence of two witnesses.

HARRY M. SPANGLER.
